Patented Feb. 29, 1916.

FIG.1.

FIG.2.

UNITED STATES PATENT OFFICE.

JOHN J. MULDOON, OF ROCHESTER, PENNSYLVANIA, ASSIGNOR OF ONE-THIRD TO
BERNARDINO VIAPRADRE AND ONE-THIRD TO MARCUS A. PETRELL, BOTH OF
ROCHESTER, PENNSYLVANIA.

RAILWAY-CAR CUSPIDOR.

1,173,729.

Specification of Letters Patent.

Patented Feb. 29, 1916.

Application filed June 21, 1915. Serial No. 35,846.

To all whom it may concern:

Be it known that I, JOHN J. MULDOON, a citizen of the United States, and resident of Rochester, in the county of Beaver and 5 State of Pennsylvania, have invented certain new and useful Improvements in Railway-Car Cuspidors, of which the following is a specification.

The primary object of this invention is to 10 provide a permanent cuspidor for railway cars, the only exposed portion thereof being its perforate top which is preferably slightly depressed beneath the floor surface, thereby facilitating the confining of expectorations 15 to such perforate top and as far as possible preventing the same from spreading over the floor.

A further purpose is to provide improved means for discharging the contents of the 20 cuspidor and at the same time maintain the latter substantially closed and thereby avoid objectionable drafts.

The discharging mechanism may be actuated by a current wheel which will be propelled automatically when the car is in motion, or the same may be driven by suitable gearing extending to a rotating part of the car structure, not shown.

In the accompanying drawings, Figure 1 30 is a view in top plan of the improved cuspidor in position in a railway car floor. Figs. 2 and 3 are, respectively, side and end elevations of the same, the floor being shown in section. Fig. 4 is a vertical longitudinal 35 section on line 4—4 of Fig. 1, and Fig. 5 is a vertical cross-section on line 5—5 of Fig. 4.

Referring to the drawings, 2 designates a railway car floor having opening 3 formed therethrough, the walls of the opening being 40 flanged at 4.

5 designates a box-like receptacle which is open and flanged outwardly around its upper edge at 6 to fit and be supported by floor flange 4. With the receptacle in position, flange 6 is slightly lower than the top surface of the floor, thereby leaving a depression 2' in the floor above the receptacle. Removably fitting within the flanged upper 7 portion of the receptacle is top or cover 50 having perforations or passages 8 which may be of grate-like or any other desired form to facilitate passage of expectorations into the receptacle. The side walls 9 of the receptacle converge downwardly, and the

same is true of the end walls 10, so that all 55 matter dropping through the grating is directed toward the means for removing the same which will now be described.

The open lower portion of the receptacle is formed with bearings 11 having the removable bottom cap portions 12 for confining the spindles 13 and 13' projecting from opposite ends of the discharging device 14. The latter is preferably of spool form, the central portion consisting of the double cone 60 15, the extremities of which terminate in the contracted neck portions 16, and at the outer sides of the latter are the single cone portions 17. Surfaces 17 are preferably in the plane of and form continuations of end 70 walls 10. The side and end walls of the receptacle are appropriately slotted or recessed to fit closely around the circular rotating part 14, the arrangement being preferably such that the lower edges 9' of walls 75 9 have a substantially scraping action on double cone 15, keeping the latter clean and tending to work all matter deposited thereon down into the neck portions 16.

Secured to the rotating discharging device 80 in each of neck portions 16 is a series of radially projecting blade-like pins 18 which move through slots 19 in walls 9 and discharge therethrough all matter that enters the receptacle from above, that is, all fluid 85 or semi-fluid matter and such solids as may be small enough to pass out or may be broken up by the action of pins 18. The double cone 15 is of such diameter as to provide sufficient slope to readily direct the 90 matter dropping thereon into one or the other of necks 16, and the same is true of matter that may drop or drip on the sloping walls of the receptacle, so that with part 14 rotating the cuspidor will be maintained 95 empty and comparatively clean.

Part 14 may be variously rotated, as by a propeller wheel 20 secured to spindle 13 which will be so arranged as to be driven by the air draft when the car is in motion. 100 A sheave 21 on the spindle may be geared to a motor, or to a rotating part of the car, for instance one of the axles. The discharging mechanism may be readily removed by detaching bearing caps 12 for the purpose 105 of flushing out the receptacle or for making repairs.

While the improved device is designed

primarily for use in railway cars, it may be utilized either in whole or in part in the floors of buildings. Being located in the floor and preferably sunk beneath its surface, it is entirely out of the way and is not subject to being upset or to injury to which a portable cuspidor is exposed.

I claim:

1. The combination of a railway car floor, 10 a spittle receiving receptacle beneath the floor having a perforate top exposed in the floor, movable means operative within the receptacle for discharging the contents thereof, and a wind wheel at the exterior of 15 the car and operatively connected to said means for actuating the same.
2. The combination of a railway car floor, a spittle receptacle mounted therein, a discharging device rotatable within the receptacle and having a spindle projecting at the exterior of the car, and a wind wheel mounted on the spindle. 20
3. A spittle receptacle open at the top and having downwardly converging walls, a rotatable device adapted to receive matter directed thereon by the sloping walls and discharge same from the receptacle, and a wind wheel at the exterior of the car and operatively connected to said device. 25
- 30 4. A spittle receptacle open at the top, a

device rotatably mounted in the receptacle and having cone-like faces terminating in contracted neck portions, and outlets for said neck portions.

5. A spittle receptacle open at the top, a 35 device rotatably mounted in the receptacle with portions of the device extending to the exterior thereof and with the walls of the receptacle shaped to closely fit the rotating device, and ejecting pins projecting from the 40 device and with slots in the receptacle walls through which the pins are adapted to pass.

6. A spittle receptacle open at the top, a 45 device rotatably mounted in the receptacle with portions of the device extending to the exterior thereof and with the walls of the receptacle shaped to closely fit the rotating device, the device having a central double cone-like portion and reversely disposed end 50 cone-like portions with the central and end cone portions uniting in contracted neck-like parts, and pins projecting radially from the neck-like parts with the walls of the receptacle slotted for the passage of said pins.

In testimony whereof I affix my signature 55 in presence of two witnesses.

JOHN J. MULDOON.
